UNITED STATES PATENT OFFICE.

EDGAR M. RAY AND ROBERT B. McCONNEX, OF DENVER, COLORADO; SAID McCONNEX ASSIGNOR OF ONE-HALF OF HIS RIGHT TO SAID RAY.

DUMP-CAR.

SPECIFICATION forming part of Letters Patent No. 704,578, dated July 15, 1902.

Application filed March 11, 1901. Serial No. 50,668. (No model.)

To all whom it may concern:

Be it known that we, EDGAR M. RAY and ROBERT B. McCONNEX, citizens of the United States, residing at Denver, in the county of 5 Arapahoe and State of Colorado, have invented certain new and useful Improvements in Dump-Cars, of which the following is a specification.

This invention relates to that class of cars 10 which are adapted to carry coal, mineral-bearing ores, gravel, sand, and like substances, to the means by which the holding portion thereof is dumped, and, finally, to the means by which the holding and dumping mechanisms are held in position during transportation, all of which will more fully hereinafter appear.

The principal object of the invention is to provide a simple, economical, and efficient 20 dump-car.

A further object is to provide a dump-car having a fixed frame with means for holding the load in position for transportation and permitting it to be dumped at desired times.

25 A further object is to provide a dumping-car having a fixed frame portion with a holding dumping-box and means for holding it in locked position, as will be hereinafter more fully described.

30 The invention consists, principally, in a dump-car in which there are combined a fixed frame portion, a body portion vibrantly held therein, and means for holding the dumping body portion in carrying position.

35 The invention consists, further, in a dumping-car in which there are combined a fixed frame portion, a dumping body portion extending longitudinally of the car and swingingly mounted in the frame portion, and 40 means for locking and holding the dumping-body in carrying position.

The invention consists, further, in a dumping-car in which there are combined a fixed frame portion and tilting dumping-boxes arranged longitudinally of the car and open at the outer side, swinging sides hinged to the frame and forming closures for the open side of the holding-boxes, and means for holding the dumping-box portions in carrying position.

50 The invention consists, further and finally,

in the features, combinations, and details of construction hereinafter described and claimed.

In the accompanying drawings, Figure 1 is 55 an end elevation of a car-body constructed in accordance with these improvements; Fig. 2, a cross-sectional elevation showing one of the boxes in dumping position, taken on lines 2 of Figs. 5 and 7; Fig. 3, a sectional plan 60 view of a portion of the car-body, taken on line 3 of Fig. 3 looking in the direction of the arrow; Fig. 4, a plan view of one end of the car-body looking at it from above; Fig. 5, a side elevation of a portion of the car-body; 65 Fig. 6, a longitudinal sectional detail taken on line 6 of Fig. 7; and Fig. 7, a plan sectional view of the underframing, taken on line 7 of Fig. 5.

In the art to which this invention relates it 70 is well known that the problem of carrying broken material—such as coal or mineral-bearing ores, gravel, and sand—and delivering it to a desired point of destination as economically as possible is one that has long interested railroads and users of railroad-cars.

In the particular class of cars to which this invention relates it is well known that the majority of such cars may be used for the purpose of carrying materials and dumping 80 them, but that, generally speaking, they are unsuited for the purpose of delivering articles, excepting by an automatic dumping process. It is often desirable, however, to have these cars so arranged that the material 85 can be shoveled out of the cars. This is especially the case in delivering coal or mineral-bearing ores in small quantities when it must be discharged by shoveling.

The principal object, therefore, of our in- 90 vention is to provide a car of the class described which is simple and economical to build and efficient in operation, one that can be used either for the purpose of automatically dumping the load or shoveling it out by 95 manual labor, all of which will be appreciated by those skilled in the art.

In illustrating and describing these improvements we have chosen to illustrate and describe them in connection with a peculiar 100 type of frame, and have only deemed it necessary to describe so much of a car as is old,

taken in connection with what we consider to be new, as will properly disclose the invention to others and enable those skilled in the art to practice the same, leaving out of consideration other and well-known parts, which, if illustrated and described herein, would only tend to confusion, prolixity, and ambiguity.

In constructing a car in accordance with these improvements we make the under-frame of center sills *a* extending longitudinally of the car and intermediate sills *b* extending likewise at a point between the sides of the car and the center sills. These sills extend outwardly at each end of the car, as shown in Figs. 1 and 2, and are tied together at the extreme ends by means of the end sills *c* and end plates *d*. To further strengthen the underframing and furnish side stakes or posts for the car, we provide a plurality of U-shaped T-beams *e*, which are arranged transversely of the car-frame underneath the sill portions above described and extend upwardly at each side of the car with the flanged portion of the beam arranged on the inner side, so that the supporting-sill may rest thereon and the sides of the car be fastened thereto. These U-shaped metallic members act in a dual capacity—that of tie rods and side stakes or posts. They are secured together longitudinally at their upper ends by means of channel-beams *f*, which tie them together in an efficient manner. The web of such channel-beams is secured to the flanges of the T-beam side posts so that they present a smooth inner surface to the interior of the car with their flanges extending outwardly. These channel-beams, which secure the U-shaped T-beams together, may be made in sections—that is, they may be made formed of two angle-irons joined together by a web-plate or may be made of one integral channel-beam to suit different circumstances or conditions. The ends of the car are formed of a steel plate *w* the entire width and depth of the body portion. To strengthen the same, end posts *g*, formed of angle-irons, are provided at each end of the car, secured together by means of the horizontal member of the end U-shaped T-beams and at their upper ends by means of angle-irons *h*, which also secure them to the upper ends of the U-shaped beams, as shown particularly in Figs. 1 and 3. One side of these end posts may be also secured to the outer intermediate sills, as shown particularly in Fig. 3. The portion of the car above described forms what we prefer to term a "fixed frame portion"—that is, such parts are rigidly secured together and the relation at all times fixed so as to practically support the movable parts and load, as hereinafter more fully described.

To provide means by which the load may be carried during transportation and dumped or discharged when the desired destination is reached, we provide what we term "dumping-box portions" *i*, which are substantially

L-shaped in cross-section and practically U-shaped in longitudinal section—that is, the box portion is open at one side and the top, or, in other words, has one side portion, a bottom portion, and two end portions, but is lacking in a top portion and one side portion. These dumping-boxes are arranged longitudinally of the car and mounted upon rock-shafts *j* and are formed of a plurality of L-shaped metal T-beams *k*, extending transversely of the box and joined together by flat plates which form the inner side, two ends, and the bottom portion. These dumping-boxes are mounted upon rock-shafts above described, which in turn have their journal portions in saddles or brackets *l* resting upon the sills of the car. A plurality or series of these supporting saddles or brackets is provided and the square rock-shafts are provided with cylindrical journals at the points in which they rotatably engage with the brackets. We prefer to provide two or more of these dumping-boxes on each side of the car arranged longitudinally therewith, so that such car may be used to carry two or more different kinds of material, and, as in the case of mineral-bearing ores, carry different grades of ore. It will be understood, however, that the car may be provided with but one of these dump portions on each side of the car and extending longitudinally thereof.

It is desirable that some means be provided when the car is in carrying position to close the outer open side of the dumping-box and also to lock such dumping-box in fixed position to carry the load. In order to accomplish this result, a swinging door *n* is provided and pivotally mounted at each side of the car, preferably to the upper fixed portion of the side, so that when it is in its closed position and the dumping-box in its carrying position, as shown in one-half of Fig. 2, the swinging door completes the closure for the open side and practically makes a complete box of it. To lock this swinging door in position, as well as to form a seal between the swinging door and the box, and thus prevent leakage of fine material, a hooked locking-plate *m* is provided, mounted upon a rock-shaft *o*, adjacent to the outer lateral free edge of the dumping-box, as shown in Fig. 2. The swinging door is provided with a lip *p*, adapted to be engaged by the hooked edge on this locking-plate, as shown in Fig. 4. The rock-shaft of this hooked plate is provided with an operating-handle *q* and one of the end stakes of the car with a link *v*, adapted to be slipped down over the free ends of the operating-handle and hold it in its locked position, which also assists in holding the dumping-box in its locked position.

To provide means by which the manual exertions of the trainman may be used to tilt the dumping-box from a carrying to a dumping position, or vice versa, a segmental geared lever *r* is provided engaging with a hand-wheel *s* by means of a train of compound

gears t , all of which enables the trainman to tilt such boxes with the least exertion possible. A pawl u may be used to engage with one of the spur-gears to assist in holding the dumping-box in locked position.

While we have described our improvements with considerable detail as to form, construction, and arrangement, we do not desire to be limited thereto unduly or any more than is pointed out in the claims. On the contrary, we contemplate all proper changes in form, construction, and arrangement, the omission of immaterial elements, and the substitution of equivalents, as necessity may demand or circumstances render expedient.

We claim—

1. In a car of the class described, the combination of a fixed frame portion, a plurality of transversely-extending saddles arranged rigidly thereon, a plurality of dumping portions vibrantly mounted upon and connected by such saddles, a rigid side portion of the fixed frame extending above and outside of the dumping portions and connecting the ends of the fixed frame, swinging doors mounted beneath and upon such rigid side portions adjacent to the outer sides of the dumping portions and dumping mechanism for dumping the dumping portions, substantially as described.

2. In a car of the class described, the combination of a fixed frame portion, a saddle mechanism mounted thereon, a plurality of dumping portions having inner inclosing sides and open outer sides and pivotally mounted upon and connected together by the saddle mechanism, a rigid side portion of the fixed frame extending above and outside of the dumping portions and connecting the ends of the fixed frame, swinging doors mounted beneath and upon such rigid side portions adjacent to the outer sides of the dumping portions and dumping mechanism for operating the dumping portions, substantially as described.

3. In a car of the class described, the combination of a fixed frame portion, a dumping portion having one side, a bottom portion and two ends vibrantly mounted therein, longitudinal beams extending above the dumping portion and connecting the upper portions of the ends of the fixed frame, a swinging door pivotally mounted on the frame portion and forming the outer side of the dumping-box portion to provide means for carrying a load, and means for holding the parts in carrying position, substantially as described.

4. In a car of the class described, the combination of a fixed frame portion provided with side posts and open at its sides and top, a longitudinal tie-plate securing the upper portion of the side posts together, a dumping-box portion substantially L-shaped in cross-section and U-shaped in longitudinal section arranged longitudinally of the car with its open sides arranged adjacent to the open sides of the frame, rock-shafts vibrantly

mounted in the frame portion and secured to the dumping-boxes for tilting the same, swinging doors pivotally secured to each side of the car to complete the closure of such side and the open side of the dumping-boxes, and means for locking the parts in carrying position, substantially as described.

5. In a car of the class described, the combination of a fixed frame portion provided with side posts and open at its sides and top, a longitudinal tie-plate securing the upper ends of the side posts together, a dumping-box portion substantially L-shaped in cross-section and U-shaped in longitudinal section arranged longitudinally of the car with their open sides arranged adjacent to the open sides of the frame, rock-shafts vibrantly mounted in the frame portion and secured to the dumping-boxes for tilting the same, swinging doors pivotally secured to the upper portion of each side of the car to complete the closure of such side and the open side of the dumping-boxes, and locking-plates pivotally secured to the lateral outer edge of the dumping-boxes and adapted to be engaged with the swinging sides of the car to lock such parts in carrying position, substantially as described.

6. In a car of the class described, the combination of a fixed frame portion provided with side and end parts rigidly secured together at their upper ends, dumping-boxes arranged on each side of the car longitudinally thereof and provided with an open top and an outer open side, rock-shafts pivotally mounted in the supporting-frame and secured to the dumping-boxes to tilt the same, longitudinal swinging doors pivotally mounted on the upper portion of each side frame of the car to complete the closure thereof and the closure of the dumping-boxes, a plate pivotally secured to the outer lateral edge of the dumping-boxes to engage the swinging door of the car-frame, means for holding the locking-plate in its locked position, and means for operating the rock-shaft to tilt the dumping-box from carrying to dumping position and vice versa, substantially as described.

7. In a car of the class described, the combination of a fixed frame portion formed of longitudinal sills and U-shaped transverse metal members which form tie-beams for the sills and side posts for the car, metallic members for tying the upper ends of the posts together, rock-shafts arranged longitudinally of the car, one at each side of the longitudinal center thereof, dumping-boxes L-shaped in cross-section and substantially U-shaped in longitudinal section secured to the rock-shafts so that they may be tilted to dumping positions, swinging doors pivotally secured to the sides of the car-frame at or near the upper portion thereof with their free edge at or near the lower side of the car to form a closure therefor and for the outer side of the dumping-boxes, hooked plates provided with rock-shafts pivotally secured to the outer

- lateral edge of the dumping-boxes adapted to engage with the free end of the swinging doors and hold the same in locked position, a lever for operating this rock-shaft and means for holding it in locked position, and means for holding and rocking the main rock-shafts and thereby tilting the dumping-boxes into carrying or dumping positions, substantially as described.
10. 8. In a car of the class described, the combination of a fixed frame portion formed of longitudinal sills, side and end posts, tie-beams securing the upper ends of such posts rigidly together, dumping-boxes arranged at each side of the car having an open top and outer open side, rock-shafts pivotally mounted on the car-frame and secured to such dumping-boxes to tilt them into their different positions, swinging doors pivotally secured to the upper sides of the car-frame to form a closure therefor and for the open sides of the dumping-boxes, a hooked plate provided with a rock-shaft by which it is secured to the outer lateral edge of the dumping-boxes and adapted to engage the swinging doors and hold the same in locked carrying position, an operating-lever secured to the rock-shaft of the hooked locking-plate, means for holding this operating-lever in locked position, and gear mechanism for operating the rock-shaft upon which the dump-boxes are tiltingly mounted, substantially as described.
9. In a car of the class described, the combination of a fixed frame portion, a dumping portion vibrantly mounted therein having an inclosing inner side and an open outer side, a rigid side portion of the fixed frame extending above the dumping portion and connecting the ends of the fixed frame, a swinging door mounted beneath and upon the rigid side portion adjacent to the open side of the dumping portion and adapted to form an outer inclosing side adjacent to such dumping portion, means for dumping the dumping portion and means for holding it in carrying position, substantially as described.
10. In a car of the class described, the combination of a fixed frame portion, a dumping portion vibrantly mounted therein an upper rigid side portion of the fixed frame extending above the dumping portion and connecting the ends of the fixed frame, a swinging door mounted beneath the rigid side portion, an upward-extending portion on the inner side of the dumping portion adapted to

contact the fixed frame when the dumping portion is in position to discharge its contents, and means for holding the dumping portion in carrying position, substantially as described.

11. In a car of the class described, the combination of a fixed frame portion provided with longitudinal sills, saddles provided with rock-shaft bearings arranged upon such sills, rock-shafts vibrantly mounted in the rock-shaft bearings and extending beneath and throughout the entire length of the dumping portions mounted thereon, a plurality of dumping portions mounted upon such rock-shafts and connected together by the saddles, and means for holding the dumping portion in carrying position, substantially as described.

12. In a car of the class described, the combination of a fixed frame portion, a plurality of saddles arranged thereon, a plurality of dumping portions pivotally mounted upon and connected by such saddles, a rigid side portion of the fixed frame extending along each side thereof above the dumping portions and connecting the ends of the fixed frame, a swinging door mounted beneath and upon the rigid side portions of the fixed frame adjacent to the dumping portions, and dumping mechanism for operating the dumping portions, substantially as described.

13. In a car of the class described, the combination of a fixed frame portion, saddle mechanism arranged thereon and provided with rock-shaft bearings adapted to support longitudinally-extending rock-shafts, a plurality of dumping portions pivotally mounted upon the rock-shafts and connected together by the saddle mechanism, a rigid side portion of the fixed frame extending along each side thereof above the dumping portions and connecting the ends of the fixed frame, a swinging door mounted beneath and upon the rigid side portions of the fixed frame adjacent to the dumping portions, a swinging door mounted beneath and upon each rigid side portion of the fixed frame adapted to form a yielding side for the adjacent dumping portion, and dumping mechanism for operating the dumping portions, substantially as described.
